CLAIM

The ornamental design for handheld vacuum cleaner with charging stand, as shown and described.

DESCRIPTION

FIG. 1 is a front, right, and top perspective view of a handheld vacuum cleaner with charging stand, showing my design.

FIG. 2 is a rear, left, and bottom perspective view thereof. FIG. 3 is a right side elevation view thereof.

FIG. 4 is a left side elevation view thereof.

FIG. 5 is a front elevation view thereof.

FIG. 6 is a rear elevation view thereof

FIG. 7 is a top plan view thereof; and,

FIG. 8 is a bottom plan view thereof.

The broken lines shown in the drawings are included for the purpose of illustrating portions of the handheld vacuum cleaner with charging stand that form no part of the claimed design.
